E. B. CLARK.
INDICATING DEVICE.
APPLICATION FILED FEB. 25, 1919.

1,393,500.

Patented Oct. 11, 1921.

Inventor:
Edward B. Clark:

John J. Pech
Atty.

UNITED STATES PATENT OFFICE.

EDWARD B. CLARK, OF GOLCONDA, ILLINOIS.

INDICATING DEVICE.

1,393,500.

Specification of Letters Patent. Patented Oct. 11, 1921.

Application filed February 25, 1919. Serial No. 279,158.

To all whom it may concern:

Be it known that I, EDWARD B. CLARK, a citizen of the United States, and a resident of Golconda, in the county of Pope and State of Illinois, have invented certain new and useful Improvements in Indicating Devices, of which the following is a full, clear, and exact description, reference being had to the accompanying drawings, forming part of this specification.

My invention relates more particularly to indicating devices intended for use on railroad and other cars wherein it is desired to indicate to the passengers the next stop of the train or car.

One object of my invention is the provision of means whereby the conductor or operator of the train may cause the operation of the device, and whereby when once set in motion the device will automatically continue to operate until it has changed its indication, whereupon it will automatically stop.

Another object of my invention is the provision of means whereby the direction of travel of the indicator may be reversed.

Other objects of my invention will appear and be described throughout the specification.

The novelty of my invention will be hereinafter more fully set forth and specifically pointed out in the claims.

In the accompanying drawing, Figure 1 is a front elevation of a device embodying my invention, a part of the curtain being broken away to show the interior.

Fig. 2 is a sectional end view of Fig. 1, the section being taken immediately inside of the right hand end wall.

Fig. 3 is a diagrammatic view showing the electrical connections.

The same numerals of reference are used to indicate identical parts in all the figures.

In the drawing 1 represents any suitable base to which the housing 2 is attached so as to be easily dismounted. The housing 2 is provided with an opening 3 through which a portion of the curtain 4 may be seen, the curtain 4 carrying the names of the station of the particular line on which the device may be used, together with such display advertising as may be desired.

The curtain 4 is attached at its ends to the rollers 5 which may be flanged as at 6

to maintain the proper alinement of the curtain.

To maintain the curtain in its proper position before the opening 3 of the housing 2, guide rollers 7 are mounted one above the other below the opening, the curtain passing from the rollers 5 over the guide rollers 7 as will be seen in Fig. 2.

Each of the rollers 5 are provided with a worm wheel 8 and a shaft 9 is mounted on a suitable bracket 10 and provided with a worm at each of its ends to engage one of the worm wheels 8, one of these worms being right hand and the other left hand. The bracket 10 is mounted upon a motor 11 so that it may oscillate thereon, the motor 11 being provided with a worm 12 meshing with a worm wheel 13 carried by the shaft 9.

Movement-limits are provided for the bracket 10, these being in the form of adjusting screws 14 carried in brackets 15 and arranged so that the depth of an engagement between the worm wheel 8 and either of the worms on the shaft 9 may be properly regulated, the upper screw controlling the lower worm and wheel.

The bracket 10 is provided with an arm 16 to which a link 17 is attached, the link being attached to a bell crank 18 from which a connecting rod 19 extends to the reversing lever 20 which operates in connection with a quadrant 21 provided with detents 22 so that the lever may be set to the neutral point as shown or to engage the curtain winding mechanism for either direction.

The connecting rod 19 is provided with a yielding connection 23 for the purpose of permitting the lever 20 to be operated even though the gearing may not be in position to properly engage, the yielding connecting forcing the gearing into proper mesh as soon as the motor 11 is set in operation.

The upper guide roller 7 is made with a conducting surface so that it may form a portion of the electrical circuit and a contact roller 24 (Figs. 2 and 3) is mounted on an arm 25 in such a manner that it may rest upon the guide roller 7 and the curtain 4 is provided with perforations dotted lines 26 (Fig. 1) through which the contact roller 24 may have contact with the guide roller 7, Fig. 3 showing the roller making its contact through one of the perforations 26 in the curtain 4.

A solenoid 27 is employed to raise the roller 24 out of contact with the roller 7 and also to move the arm 28 until this arm makes contact with the pin 29 and brings 5 the blade 30 into contact with the pins 31 and 32. A solenoid 33 is used to hold the arm 28 in contact with the pins 29, 31 and 32. A solenoid 34 is used to restore the arm 28 to the position shown in Figs. 2 and 3 at 10 the end of each operation of the device.

The electrical connections are as follows: Starting from any suitable source of current supply 35 one conductor 36 is led to the pin 32 and to one terminal of the motor 11; a branch 37 being led to any suitable push button 38 which serves the function of a starting switch and may be located at any convenient point in the car. A conductor 39 is led from the other terminal 20 of current supply and has a branch leading to the solenoid 27, a second branch to the solenoid 34 and is then led to the support for the bar 28. The other terminal of the solenoid 27 is connected as at 40 to 25 the push button 38 while the other terminal of the solenoid 34 is connected as at 41 to the guide roller 7, the contact roller 24 and arm 25 being connected as at 42 to the pin 31. The pin 29 is electrically connected to 30 one terminal of the solenoid 33 as at 43, the other terminal being connected as at 44 to the electric motor 11.

The flow of current in the various circuits thus provided, is as follows. 35 With the parts in the position shown in Figs. 2 and 3 the operator desires to cause the display of the next succeeding signal or indication on the curtain 4 and to do this he presses the push button 38 thus closing 40 the circuit through the solenoid 27 and energizing its core and raising the roller 24 from the roller 7, the arm 25 being magnetic, and also moving the bar 28 to its point of contact with the pin 29, the bar 45 being also affected by magnetism. As soon as the bar 28 makes its contact with the pin 29 the circuit is established through the motor the current flowing from the conductor 39 through the bar 28, pin 29, conductor 43, solenoid 33, conductor 44, motor 11, conductor 36 thus completing the circuit and energizing the core of the solenoid 33 to hold the bar 28 in its contact position, the 50 making of this contact starting the electric motor and causing the movement of the curtain 4 through the gearing previously described. 55 The blade 30 establishes connection between the pins 31 and 32 as soon as the bar 60 28 makes its contact with the pin 29 the blade 30 being preferably insulated as at 45 from the bar 28, the circuit thus established being part of the circuit brought into operation for stopping the device though this 65 circuit is not completed until the next suc-

ceeding opening 26 in the curtain permits the roller 24 to contact with the guide roller 27 the circuit then being from the conductor 39 through the solenoid 34, conductor 41, roller 7, roller 24, arm 25, conductor 42, 70 pin 31, blade 30, pin 32 and conductor 36 thus forming a circuit which energizes the core of the solenoid 34 and pulls the bar out of its position in contact with the pin 29 and to the position shown in Fig. 3, thus 75 breaking the circuit through the motor and also breaking the circuit through the contact roller, a light spring 46 being employed to hold the bar 28 out of contact with the pin 29. 80

The solenoid 34 is of sufficient size to overcome the attraction of the solenoid 33 so that at the instant of the contact of the roller 24 with the guide roller 27 the bar 28 is pulled away from the solenoid 33 as 85 previously described.

The pins 29, 31 and 32 are preferably made so that they may be adjusted to properly establish the circuits called for.

It is not necessary that the operator hold 90 the push button 38 on contact longer than in instant for the reason that as soon as the solenoid 27 is energized and the motor connection established, the curtain 4 is moved so that the opening of the circuit through 95 the solenoid 27 only permits the roller 24 to drop upon the curtain, the curtain being used as an insulator between this roller and the guide roller 7 until the next succeeding opening 26 in the curtain 4 comes under the 100 roller 24 whereupon the stopping circuit is established through the solenoid 34.

Having thus fully described my invention, I claim:

1. In an indicating device the combination of a curtain having display indications thereon, rollers upon which said curtain may be wound, gearing for alternately driving said rollers in a direction to wind the curtain thereon, means for shifting said gearing into engagement for driving either of said rollers, a yielding connection in the shifting means whereby a portion thereof may be fully operated to operate the balance when proper driving relations are 110 established, means for driving the gearing and means controlled by the position of the curtain for stopping the driving means.

2. In an indicating device the combination of a curtain having display indications 115 thereon, rollers provided with gearing for moving the curtain, an electric motor for operating the gearing to drive the rollers, a switch for establishing electrical connections for said motor, a solenoid for closing 120 said switch, a solenoid for opening said switch, and a contact controlled by the position of the curtain for energizing the solenoid for opening the switch.

3. In an indicating device the combina- 130

tion of a curtain having display indications thereon, rollers provided with gearing for moving the curtain, an electric motor for operating the gearing to drive the rollers, a switch for establishing electrical connections for said motor, a solenoid for closing said switch, a solenoid for holding said switch in closed position and included in the motor circuit, a solenoid for opening said switch, and a contact operated by the position of the curtain to energize the solenoid for opening the switch to stop the motor.

EDWARD B. CLARK.
